UNITED STATES PATENT OFFICE.

JOHN S. MYERS, OF PHILADELPHIA, PENNSYLVANIA, ASSIGNOR TO WESTINGHOUSE ELECTRIC AND MANUFACTURING COMPANY, A CORPORATION OF PENNSYLVANIA.

GOVERNING APPARATUS.

Application filed September 12, 1923. Serial No. 662,316.

To all whom it may concern:

Be it known that I, JOHN S. MYERS, a citizen of the United States, and a resident of Philadelphia, in the county of Philadelphia and State of Pennsylvania, have invented a new and useful Improvement in Governing Apparatus, of which the following is a specification.

My invention relates to fluid-governing apparatus of the character referred to in the application of Henry F. Schmidt, Serial No. 604,038, filed November 29, 1922, and assigned to the Westinghouse Electric and Manufacturing Company, and it has for its object to provide apparatus of this character which shall be capable of effectively performing governing operations while employing a less quantity of motive fluid for its actuation.

More particularly, my invention consists in the provision of an operating piston which has a single face subject to the effect of fluid pressure in order to move the operating piston in one direction, the piston valve for the operating piston and a piston portion defined by a stem of the operating piston being depended upon to afford sufficient piston area to secure operation of the operating piston and of its valve in the other direction.

Apparatus made in accordance with my invention is illustrated in the accompanying drawings, forming a part of this application, in which Fig. 1 is a view, partly in elevation and partly in section, showing a prime mover with my improved governing apparatus applied thereto; Fig. 2 is a sectional view of the governing apparatus, and Fig. 3 is a sectional view taken along the line III—III of Fig. 2.

Referring now more particularly to the drawings for a detailed description of my invention, I show suitable apparatus, such as a turbine 10, having an admission valve 11 whose position is determined by fluid-governing apparatus, at 12, which is supplied with fluid under pressure from the impeller 13 driven by the shaft 13' of the turbine.

The governing apparatus, at 12, com-

prises a housing 14, which is provided with an operating cylinder 15 and with a supply chamber 16, the latter being connected, by means of a conduit 17, to the housing 18 of the impeller 13, so that fluid under pressure, which varies as the square of the speed of the turbine shaft 14, is supplied to the supply chamber 16.

A piston member 20 is arranged within the housing 14 and it has an operating piston portion 21 which is arranged within the operating cylinder 15. The piston portion 21 is provided with a piston face 22, which is, in operation, subject to the effect of fluid under pressure in a manner to be described. An exhaust connection 23 is provided for the operating cylinder 15 at the end of the latter opposite to said piston face 22.

The piston member 20 is preferably made hollow, and, in addition to the piston portion 21, it is provided with upper and lower hollow stem portions 24 and 25, the first stem portion being connected to a rod 26 which is connected to a lever 27, the latter, in turn, being pivotally connected to the stem 28 of the valve 11. The other hollow stem 25 of the piston member 20 extends downwardly and into the supply chamber 16 and is, at all times, subject to the fluid under pressure within the supply chamber 16, tending to force it upwardly.

The operating cylinder 15 is provided with head portions 29 and 30 which cooperate with the hollow stems 24 and 25, respectively, in a fluid tight manner.

The operating piston portion 21 is provided with upper ports 31 leading from the interior of the hollow thereof to the upper face 22 and with another series of ports 32 leading from the hollow thereof to the space beneath the piston portion 21. A hollow piston valve 24 is arranged within the piston member 20 and it is provided with ports 33, which, when in registry with the ports 31, permit of the passage of fluid under pressure from the supply chamber 16 to the upper piston face 22. The area at the upper piston face 22 is made greater than the area of the stem portion 25, with

the result that, upon the admission of fluid pressure thereto, the piston portion 21 is moved downwardly. The hollow piston valve member 34 is also provided with a constricted portion 36, which, when the blocking portion 37, separating the ports 35 from the constricted portion 36, is moved upwardly sufficiently to afford communication of the space above the piston portion 21 through the ports 31, the constricted portion 36, and ports 32 with the space below the piston portion 21, allows for the exhaust of fluid above the piston portion 21 to the space below the latter and to the exhaust connection 23.

As already pointed out in the application of Henry F. Schmidt aforesaid, the hollow piston valve member 34 is closed at its upper end by a suitable piston portion 38 and it is connected to the piston member by means of a large spring 39 which serves to bias the piston valve 34 downwardly with respect to the piston member 20. The piston valve member 34 is also connected to the bottom of the housing 14 by means of a small scale spring 40 which serves to bias the piston valve member downwardly with respect to the housing 14. The purpose of the large spring is to afford high resistance to fluid pressure and the purpose of the smaller or scale spring is to permit of variations in the aggregate of opposing spring pressure.

As further pointed out in said application of Henry F. Schmidt, a single spring of adequate strength, in order to give the requisite movement for valve operation, would be inordinately long. On the other hand, a spring of reasonable length for the required deflection would be too weak to secure proper operation and to withstand fluid pressures involved with apparatus of this character. Consequently, the large spring 39 is of the floating type and it carries the major portion of the load resisting the fluid pressure although its deflection in operation is very small. The scale spring 40 affords additional resistance and the extent of its deflection is dependent upon the fluid pressure, which, in turn, depends upon the speed.

The effect of the load spring 39 and of the scale spring 40 will be clearer from a brief statement of the operation of the apparatus so far described. Assuming that all parts are at rest and that the turbine 10 is being started and that there is no pressure within the supply chamber 16, the large spring 39 has pulled the piston valve 34 to its lowest position relative to the operating piston member 20 and the small spring 40 has pulled the piston valve 34 and with it the operating piston member 20 to its lowest position with respect to the cylinder 15. In this position the turbine admission valve 11 is wide open. With no pressure in the sup-

ply chamber 16 the port 35 is in communication with the port 41 leading to the upper face 22 of the piston portion 21. When the turbine 10 is started fluid pressure from the impeller 13 begins to build up in the supply chamber 16 beneath the piston portion 25, tending to force it upwardly. At the same time, it builds up above the piston portion 21 against the face 22 tending to force it downwardly. Inasmuch as the area of the face 22 is greater than that of the stem portion 25, the fluid pressure acting against the greater area of the face 22 holds the piston 20 down. The piston 20 remains in this position until the fluid pressure builds up sufficiently in response to the increasing speed of the turbine, that acting against the piston portion 38 of the piston valve 34 it overcomes the force exerted by the springs 39 and 40, which are acting to pull the piston valve 34 to its lowest position relative to the operating piston 20 and moves the piston valve 34 upwardly until the cut-off portion 37 comes opposite the port 31 in the position shown in Fig. 2. The fluid already above the piston face 22 is now trapped within the cylinder and, with the fluid pressure acting continuously against the stem portion 25, the operating piston 20 is rigidly blocked in the position shown. Assuming now that the pressure of fluid in the supply chamber 16 further increases due to a further increase in speed of the turbine 10, then the fluid pressure acts upon the piston portion 38 of the piston valve to further raise the latter so as to place the constricted portion 36 in communication with the ports 31 and 32 so that the space above the operating piston portion 21 may be placed in communication with the exhaust. This movement of the piston valve 34 involves deflection of the springs 39 and 40 to the same extent, but, as the spring 39 is much stronger, the major portion of the increased pressure is resisted by it.

As soon as the space above the operating piston 21 is placed in communication with the exhaust, as just pointed out, fluid, under pressure in the supply chamber 16 is then effective upon an area, whose diameter is that of the lower stem 25, to move the piston member 20 upwardly. As this upward movement continues, the scale spring undergoes more deflection and therefore takes some of the load borne by the large spring 39; and this upward movement continues with the transfer of load from the large spring to the scale spring until the piston valve 34 moves relatively to the piston member 20 so as to bring the portion 37 into cut-off relation with respect to the ports 31, whereupon, the operating piston member 20 is maintained in its acquired position until a further change in fluid pressure takes place.

Assuming that the speed of the turbine drops, as is the case when overloaded, the first effect of diminished fluid pressure in the supply chamber 16 is for the piston valve 34 to move downwardly under the influence of the springs 39 and 40. Such downward movement results, of course, in the unloading of the spring 39 to a greater extent than the spring 40. Just as soon as downward movement of the piston valve 34 commences, the ports 35 are brought into communication with the ports 31 so that fluid under pressure is supplied from the supply chamber 16 to the operating cylinder 15 above the operating piston portion 21 so that the latter is moved downwardly. Downward movement of the piston valve 34 and of the piston member 20 will continue until the piston valve 34 is arrested in its motion sufficiently to bring the cut-off portions 37 in registry with the ports 31. The latter operation occurs when the decrease in pressure of fluid is balanced by the small spring 40, the large spring 39 regaining its normal load which it has whenever the portions are in cut-off position.

From the structure described, it will be apparent that the operating piston member 20 is moved downwardly by the application of fluid under pressure to the upper piston face 22, whereas upward movement of the piston member 20 is secured by the application of pressure to the lower face of the stem 25 and to the lower piston surface of the piston valve 34 and of the head portion 38, so that the total effective lower piston area has the diameter of the lower stem portion 25. In this structure, therefore, the controlling element 20 of the governor has a single acting piston portion 21 within the operating cylinder 15, against which fluid pressure acts only on the upper face 22, the lower face being at all times connected to the exhaust.

In the Schmidt construction aforesaid, the area of the operating piston against which the fluid pressure acts to force it upward is that of the lower portion 25 plus the annular area of the lower side of the portion 21, while the area against which the fluid pressure acts to force the operating piston downward is the annular area of the face 22 of the portion 21, which must always be less than the area against which the pressure acts to force the operating piston upward. This construction requires more fluid for operating than in my modification.

It will be apparent that with my modified construction the relative areas of the piston against which the fluid acts to force it upward or to force it downward are within the control of the designer and may be modified to suit the particular requirements. In this way, I provide for a saving of motive fluid to the extent of that necessary

to actuate the lower face of the operating piston in the aforesaid Schmidt construction and, as a result, provide an apparatus more sensitive to the rotational velocity of the impeller.

In order that the governing apparatus referred to may be adjusted for operation at different speeds, it is necessary that provision be made for changing the tension of the large spring 39. Accordingly, I provide a central screw member 42 engaged within the lower end of the spring 39 and having threaded connection with respect to a sleeve 43, carried by the piston member 20, and having a splined connection with respect to a wormwheel or gear 44 meshing with a worm 45. The central screw member 42 is held against rotation by a spline connection 42' with a ring 42'', which is in turn secured to the piston portion 25. Turning of the worm 45 in one direction or the other has the effect of elevating or lowering the stem 42 in order to decrease or to increase the tension of the spring 39. Change in tension of the spring 39 results in a change in the pressure necessary to bring the piston valve 34 and the piston member 20 in such relative positions that the portions 37 occupy a cut-off position with respect to the ports 31. In other words, change in the tension of the spring 39 means a change in the base load or pressure, and this, in turn, calls for a change in speed of the impeller 13 and, therefore, of the turbine 10. With a given adjustment of the load spring 39, any fluctuations in load are taken care of by the fluctuations in speed within the limits of the scale spring 40.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a fluid-pressure actuated governing apparatus, the combination of a controlling element having a single-acting operating piston portion actuated in one direction by intermittent admission of fluid under pressure thereagainst and a stem portion subjected at all times to fluid under pressure for moving the controlling element in the opposite direction, a valve for admitting and exhausting motive fluid to the operating piston portion, means for biasing the valve toward a fixed position relative to the controlling element, and further means for biasing the valve toward a stationary element.

2. In fluid-pressure actuated apparatus, the combination of a piston having a single-

acting operating portion, a valve within the piston for admitting and exhausting motive fluid to the active face of the single-acting portion, a spring for connecting the piston and the valve, and a second spring for connecting the valve to a stationary part.

3. In fluid-pressure actuated apparatus, the combination of a hollow-piston member having a piston portion and guide portions, 10 a piston within the piston member for controlling the admission of motive fluid to one face of the piston portion to secure actuation of the piston member in one direction, spring means connecting the piston member and the piston, one face of a guide stem of said piston member and said piston serving as a piston to secure actuation of the piston member in the other direction, and a second spring connected to the piston and 20 to a stationary part.

4. In fluid-pressure actuated apparatus, the combination of a housing providing an operating cylinder and a fluid-supply chamber, a piston member having a piston portion 25 fitting within the operating cylinder and a stem portion extending into the supply chamber, a piston within the hollow-piston member for controlling the admission of motive fluid from the supply chamber to one face of the piston portion and the exhaust of fluid therefrom, spring means 30 for connecting the piston member to the piston, and other spring means for connecting the piston to the housing.

35 5. In fluid-pressure actuated apparatus, the combination of a housing having an operating cylinder and a motive fluid supply chamber, an operating piston within the cylinder and having a stem extending into the 40 supply chamber, a valve for controlling the admission of motive fluid from the supply chamber to one face of the piston and the exhaust of fluid therefrom, a spring for connecting the valve to the piston, and a second 45 spring for connecting the valve to the housing.

6. In fluid-pressure actuated apparatus, the combination of a housing having an operating cylinder and a motive-fluid supply chamber, an operating piston within the 50 cylinder and having a stem extending into the supply chamber, said operating cylinder having an exhaust connection at one end, a piston for controlling the admission of 55 fluid from said chamber to one face of said operating piston and the exhaust of fluid from the latter to the other side of said piston and to the exhaust connection, a spring for connecting the operating piston to the 60 valve, and a second spring connected to the valve and to the housing.

65 7. In fluid-pressure actuated apparatus, the combination of a part to be governed, a housing having an operating cylinder and a fluid supply chamber, a hollow operating

piston member having a piston portion fitting in the operating cylinder and having upper and lower stem portions, the upper stem portion being connected to the operating element and the lower stem portion extending into the supply chamber, a piston within the hollow piston member for controlling the admission and exhaust of fluid to one face of said piston portion, a spring for connecting the piston member to the valve and opposing the effect of fluid pressure applied to the latter, and a second spring connected to the valve and to the housing and also opposing the effect of fluid pressure applied to the valve.

8. In fluid-pressure actuated apparatus, the combination of a housing having an operating cylinder and a fluid-supply chamber, a hollow-operating piston within the cylinder, a valve member within the piston and having a piston portion, spring means for connecting the valve member to the operating piston and spring means for connecting the valve member to the housing.

9. In fluid-pressure actuated apparatus, the combination of a housing having an operating cylinder and a supply chamber, the operating cylinder having an exhaust connection at one end, an operating piston within the operating cylinder, a valve for controlling the admission of fluid from the supply chamber to the face of said operating piston opposite to the exhaust connection and the exhaust of fluid from said face of the operating piston to the other side of the latter and to the exhaust connection, a spring for connecting the valve to the piston, and a second spring for connecting the valve to the housing.

10. In fluid-pressure actuated apparatus, the combination of a housing having an operating cylinder and a supply chamber, the operating cylinder having an exhaust connection at one end thereof, an operating piston within the operating cylinder and having a stem extending into the supply chamber, a piston valve within the operating piston and the stem for controlling the admission of fluid from the supply chamber to one face of said operating piston and the exhaust of fluid from the latter to said exhaust connection, a spring for connecting the operating piston and the piston valve, and a second spring for connecting the piston valve to the housing, said piston valve having a piston portion which is effective with the piston area of the lower face of said stem to provide for movement of the operating piston and of the valve in a direction opposite to movement of the operating piston in response to fluid pressure admitted to said face.

11. In fluid-pressure actuated apparatus, the combination of a housing having an operating cylinder, a hollow piston member

within the housing and having a piston portion within the operating cylinder and a stem provided with a piston portion, a piston valve for controlling the admission of fluid to one face of the operating-piston portion and having a piston portion, the latter piston portion and the piston portion of said stem being arranged oppositely to the

effective face of said operating piston portion, a spring for connecting the piston member to the piston valve, and a spring for connecting the piston valve to the housing. ¹⁰

In testimony whereof, I have hereunto subscribed my name this 7th day of September, 1923.

JOHN S. MYERS.
